CAN FILLING MACHINE

Charles H. Ayars, Salem, N. J., assignor to Ayars
Machine Company, Salem, N. J., a corporation
of New Jersey

Original application November 10, 1936, Serial
No. 110,053. Divided and this application No-
vember 23, 1936, Serial No. 112,278

23 Claims. (Cl. 223—102)

This invention relates to can filling machinery, and has special reference to machinery which deposits into cans both solid and liquid material. It has to do with machinery of the foregoing type in which both the solid and liquid materials are measured before deposit into the cans, and the measuring means employed for both the solid and liquid materials are adjustable to suit every requirement.

10 This application is a division of an application filed by me on the 10th day of November, 1936, Serial No. 110,053.

The object of the present invention is to provide in machines of the foregoing type, means for indicating the capacities of the measuring devices.

Another object of the invention is to provide capacity indicating means which are automatically operated by the means which controls the capacities of the measuring devices.

Still another object of the invention is to provide means whereby the capacities of the measuring devices may be readily changed to suit grading of materials of each canner or packer.

25 According to the invention, the can filling machine which has means for feeding cans into operative position for filling, and a pair of measuring devices, each comprising an upper and lower turret member providing telescopic cups, one of the devices having means for supplying discrete solid material to its cups, and the other having means for supplying liquid to its cups, a distributing member having funnels each adapted to successively receive the contents of a solid material cup and a liquid material cup and to direct the same into a can to be filled, each of said measuring devices having a shaft attached to the upper turret and provided with means for raising and lowering said shaft, and means operated by 30 said last means for indicating the capacities of the cups.

The drawings illustrate an embodiment of the invention, and the views therein are as follows:

Figure 1 is a vertical sectional view of a part of the machine, the can feeding mechanism and legs of the machine being broken away.

Figure 2 is a fragmentary side view of the machine and shows the mechanism for adjusting the discrete solid material measuring pockets, and 45 the means for indicating the capacities thereof.

Figure 3 is an end view of the same,

Figure 4 is a fragmentary view of mechanism employed for adjusting the capacities of the liquid measuring cups and the cooperative means 50 for indicating the capacities thereof.

Figure 5 is a fragmentary end view of the same.

Figure 6 is a side view of a button employed for fixing a desired capacity on the indicating dial,

Figure 7 is a fragmentary sectional view taken on the line 7—7 of Figure 1, and

Figures 8 and 9 are small detail vertical sectional views showing split turret shafts.

In each of the figures of the drawings, like characteristics indicate like parts.

In the application above referred to, there is shown a machine which, in many respects, corresponds with the machine of the present invention, except that in the parent application, the machine is provided with a pre-brining device, 15 and with governing means for preventing the supply of liquid material to the machine, except when the machine is in operation. The present invention is directed to can feeding machinery generally.

The cans A are moved on the table 9 by a star wheel 11, which has a gear 12 operated by the gear 13 on the can feed shaft 14. The cans, when filled, are removed from the table 9, and contact with the star wheel 11 by means of a star wheel 16, and rails which are clearly shown in Figure 2 of the application hereinbefore referred to. The machine is driven through a bevel gear 17 meshing with a bevel gear 18 mounted on a hollow shaft 19. The funnel casting 21 has funnels 22 for liquid material and funnels 23 for discrete solid material, and this funnel casting has a depending sleeve 24 which is secured to the hollow shaft by a set screw 26. Immediately below the funnel casting is an external ring gear 27 which has collared apertures 28, which apertures are aligned with the bottoms of the funnels 23, and this ring gear 27 has a set screw 29 connecting the same with the depending sleeve 24 of the funnel casting, so that said parts will rotate together upon the turning of the hollow shaft 19. The funnel casting rotates on a bed plate 31, and its upper surface is provided with a plate or platform 32 which has an opening 33 for permitting material to be dropped therethrough from the 40 measuring devices mounted on said plate 32.

The discrete solid material measuring device consists of a lower turret 34 and an upper turret 36. The lower turret member has circular upstanding flanges 37, while the upper turret 36 has depending circular collars 38 which fit within the upstanding circular collars of the flanges of the lower turret member 34. The lower turret member 34 is fixed to the hollow shaft 19. The upper turret member 36 has a hub 39 with a re- 55

cess 41 into which the end of a solid shaft 42 extends, and is keyed therein. This shaft 42 extends down through the hollow shaft and emerges from the lower end thereof, as shown in Figures 5 1 and 2. The hub 39 has an extension 43 to which is secured by a key 44 a pinion 46. This pinion meshes with an idler pinion 47 which, in turn, meshes with an internal ring gear 48 on the inside of the hopper casting 49. This hopper 10 casting 49 is stationary whereas the ring gear 48 is secured to the funnel or hopper 51. When the hollow shaft 19 is rotated by means of the bevel gears 17 and 18, the lower turret member 34 is turned thereby, and since its upstanding flanges 15 receive the depending flanges 38 of the upper turret member 36 to form the cups B, the upper turret casting will be rotated therewith, so that the pinion 46 will be rotated, which will impart a rotary motion to the funnel 51 which contains 20 the discrete solid material for supplying the cups B.

Referring now to Figures 2 and 3, the bottom of the solid shaft 42, which extends through the hollow shaft 17 rests within a socket 52 in the 25 stirrup 50 of a capacity regulating member 53. This member has a vertical hole 54, so that it fits onto a shaft 56 which is secured to a cross plate 57 at 58. The regulating member is also provided with an extension 59 and a lug 61. This 30 ing is screw threaded and engages a screw 62 which has a bearing 63 while collars 64 and 66 prevent vertical movement of said screw. The upper end of the screw is provided with a bevel gear 67 which meshes with a bevel gear 68 on the 35 inner end of a shaft 69, which said shaft is mounted in an upstanding bearing 71, and provided at its outer end with a hand wheel 72. The extension 59 has a link or connecting rod 73 connected therewith, and the upper end of said 40 link is connected with a rack 74, which is slidably mounted at the rear of an indicating dial 76. This rack is slideable through means of a vertical slot 77 and screws 78 fitting into the dial. The dial has a screw post 79 fitting through the 45 center of the same, and on the rear thereof is fixed a pinion 81 meshing with the rack 74, while the front end thereof is provided with a finger or pointer 82, so that upon the movement of the capacity regulating member 53 through the 50 manual operation of the hand wheel 72, the toothed rack 74 will rotate the pinion 81, and, therefore, will rotate the finger or hand 82 at the front of the dial. This dial is mounted by means of bolts 83 on the plate or platform 32.

55 It is customary, among canners or packers, to grade material which they can, for instance peas, and peas are usually graded according to size, and each packer may have a different standard of grading, that is to say, peas up to a certain 60 diameter may be called "Grade 1", peas of the next larger diameter "Grade 2", those a little larger "Grade 3", etc. In order that the machine may be accurately set for placing in each can the desired amount of discrete solids, such 65 as peas for each and every grade, it will be necessary to set the machine according to different indications for different canners. The dial 76, therefore, is provided with a circle of small holes 84 and buttons 86 (see Figure 6) having spring 70 ends 87 are provided for slipping into the dial, so that when a canner has found the exact quantity of peas or other discrete solids desired for each grade, he may place these buttons in the holes aligning with the finger or hand 82, when 75 the proper setting is obtained. The buttons,

of course, may be marked "1, 2, 3, 4, etc." so that thereafter the operator of the canning machine need only turn the hand wheel 72 until the finger 82 points to the grade of material which he is about to place in the cans, and he is thereby assured that the lower and upper funnel castings 34 and 36 have their telescopic cups B of proper capacity for placing into the cans the required volume of material.

Referring now to Figure 1, the hollow shaft 19 is provided with a bevel gear 88, which meshes with a bevel gear 89 on the bottom of a hollow shaft 91. This hollow shaft extends obliquely, and through a bearing 92 on the table 9, and through a bearing on an oblique extension 93 15 of the bed plate 31. The shaft also passes up through a bearing 94 on the turret plate 96 of the liquid tank 97. Mounted on the turret plate 96 is a lower turret member 98 which has an upstanding flange 99 surrounding an upstanding 20 flange 101 of the turret plate 96. The hollow shaft extends above these upstanding flanges, and is secured at its upper end by means of a key 102 to a driving disk 103. This driving disk has depending arms 104 which engage lugs 106 of 25 the lower turret member 98, while the upper turret member 107 has depending pins 108, which are adapted to pass through holes 109 in the driving disk 103, so that upon the rotation of the hollow shaft 91, the lower turret member 30 and upper turret member will rotate in unison, while the upper turret member is provided with plugs 111 which are adapted to fit within the liquid cups C on the lower turret member 98, and regulate the capacity of said cups by means 35 of their position therein. The upper turret 107 is secured to the upper end of a shaft 112 by means of a set screw 113, and said shaft extends down through the hollow shaft 91, and emerges from the bottom thereof. The funnel casting 21 40 is substantially the same as funnel casting 46 shown in Figures 3, 5, and 13 to 16 of applicant's Patent No. 1,533,536, granted April 14, 1925, and its utility in combination with the telescopic 45 cups B and C of the turret members is explained 50 in detail in that patent, particularly as to the timing of the deposits of discrete solid materials from the cups B and liquid from the cups C into the pockets of the casting. The principle there described and explained in detail is exactly the 55 same as the principle of mechanism of this machine insofar as these parts are concerned, and it will suffice to say that discrete solid material is deposited into the funnels 23 from the cups B prior to the deposit of liquid material into 60 the funnels 22 from the cups C. The present invention makes no change whatever in this principle of operation.

The bottom end of the shaft 112 fits within a 65 socket 114 in the stirrup 116 of a capacity regulating member 117. This capacity regulating member is substantially the same as the capacity regulating member 53, and has a hole 118 through which a shaft 119 extends. It is also provided with a screw 121 held against vertical movement 70 and provided at its upper end with a vertical gear 122 which meshes with a bevel gear 123 on the inner end of a shaft 124. This shaft is mounted in the upstanding member 126, and is provided at its outer end with a hand wheel 127. The capacity regulating member has an overhanging arm 128 to which a link 129 is pivotally connected at 131, while the upper end of said link is pivotally connected at 132 to a toothed 75 rack 133. This rack meshes with a pinion 134 80

mounted on a shouldered screw 136 at the center of a dial 137, and the front end of said shouldered screw is provided with a finger or pointer 138. The toothed rack 133 has a slot 139, while screws 141 fastened into the back of said dial permit the upward and downward movement of said rack while still maintaining the same in mesh with the pinion 134. This dial 137 is also provided with a circle of small holes 142 for receiving the buttons 86 shown in Figure 6, and for the same purpose explained in connection with Figures 2 and 3. It will, of course, be obvious that upon the changing of grades of, for instance, peas, beans or the like, the amount of liquid which will surround and cover the same will vary with the changing of grades and the capacities of the liquid cups C must, therefore, be changed upon changing grade, in the same manner as the cups B are changed for changing the capacity for different grades of discrete solid material. It will readily be seen that upon the turning of the hand wheel 127, the capacity regulating member 117 will be moved, and the weight of the upper turret member 107 will hold the shaft 112 down in the hollow shaft 91, so that if it is desired to lower the plugs 111 in the cups C, so as to decrease the volume thereof, the hand wheel 127 being turned to lower the capacity regulating member 117, the shaft 112 will follow the movement of said capacity regulating member. Of course, to increase the capacity, the upper turret member 107 will be raised, and as the shaft 91 is raised, the plugs 111 are pushed upward so that a smaller portion thereof will be within the cups C.

In each instance, it will be seen that the finger or pointer 138 on the dial 137 will be moved by virtue of the pivotally mounted link 129 carrying the toothed rack 133 which meshes with the pin 134. So that it will readily be seen that once the amount of liquid required in a can when the number 1 grade peas are being deposited, when once set can have one of the buttons 86 inserted in the small hole 142 directly opposite the position of the finger or pointer 138 so that thereafter when the grade 1 pea is about to be placed in cans, both the discrete solid material dial and the liquid dial may be made to indicate that the number 1 grade is about to be deposited, and the operator is thereby assured that the necessary amount of solids and liquids will be deposited in each can. Likewise the machine may be set for other grades.

If desired, the shafts 42 and 112 may be broken at X and Z (see Figs. 8 and 9), so as to provide upper stub shafts which will rotate with respective turrets, while the lower part of the interior shafts can remain stationary. In such a case when it is desired to wash the machine by removing the upper turrets of both devices, only the small stub shafts will need be withdrawn from their respective hollow shafts.

The construction of the canning machine described herein is such that the same can be readily kept in a clean and sanitary condition without the necessity of unscrewing or unlocking any parts, and the construction is such that even the most unskilled operator can remove the upper turrets and their associated parts and when placing the same together again can place them in no manner other than the correct way.

Of course, the can filling machine illustrated and described herein may be varied and changed in many ways without departing from the invention herein set forth and hereafter claimed.

The invention is hereby claimed as follows:

1. A can filling machine having a measuring device comprising telescopic pockets, said device having a longitudinally slidable shaft for regulating the capacities of said telescopic pockets, and a dial having a finger rotated by the sliding of said shaft for indicating the capacities of said telescopic cups.

2. A can filling machine having telescopic means for measuring material to be deposited in cans, a longitudinally slidable shaft for regulating the capacity of said telescopic means, and a dial having a gear operated finger rotated by the sliding of said shaft for indicating the capacity of said telescopic means.

3. A can filling machine having telescopic means for measuring material to be deposited into cans, a longitudinally slidable shaft for regulating the capacity of said telescopic means, manually operable means mounted on the machine frame and associated with said shaft for adjusting same, a dial mounted on said machine, a finger rotatably mounted on said dial, and means connected with said manually operable means for rotating said finger to indicate the capacity of said telescopic means.

4. A can filling machine having telescopic means for measuring material to be deposited into cans, an adjustable shaft for regulating the capacity of said telescopic means, manually operable means associated with said shaft for adjusting same, a dial mounted on said machine, a finger rotatably mounted on said dial, a pinion on said finger, and a toothed rack meshing with said pinion and operably connected with said manually operable means for rotating said finger to indicate on said dial the capacity of said telescopic means.

5. A can filling machine having telescopic means for measuring material to be deposited into cans, a longitudinally slidable shaft for regulating the capacity of said telescopic means, an adjusting member mounted on the machine frame and associated with said shaft, manually operable screw means for operating said adjusting member to slide said shaft, a dial mounted on said machine, a finger rotatably mounted on said dial, and means connected with said adjusting member for rotating said finger to indicate the capacity of said telescopic means.

6. A can filling machine having telescopic means for measuring material to be deposited into cans, an adjustable shaft for regulating the capacity of said telescopic means, an adjusting member associated with said shaft, manually operable screw means for operating said adjusting member to move said shaft, a dial mounted on said machine, a finger rotatably mounted on said dial, a pinion on said finger, and a toothed rack meshing with said pinion and operably connected with said adjusting member for rotating said finger to indicate on said dial the capacity of said telescopic means.

7. In a can filling machine having devices for measuring material to be deposited in cans, means for adjusting said measuring devices for various capacities, a dial having means for securing indicia thereon, and a finger rotatable on said dial and operated through the means for adjusting the measuring devices whereby the capacities of said devices are indicated by the positions of said finger.

8. In a can filling machine having devices for measuring material to be deposited in cans, means for adjusting said measuring devices for various

5 capacities, a dial having openings for securing grade indicating buttons thereon, and a finger rotatable on said dial and operated through the means for adjusting the measuring devices whereby the capacities of said devices are indicated by the positions of said finger.

9. A can filling machine having a measuring device comprising upper and lower turrets having telescopic measuring cups, a hollow shaft connected to the lower turret for rotating the device, a shaft longitudinally slidable within said hollow shaft and having its upper end connected to said upper turret and its lower end extending from the bottom of said hollow shaft, means mounted on the machine frame and connecting the extending end of said internal shaft for moving same longitudinally to alter the capacity of said cups, and means rotated by the operation of said last named means for indicating the capacities of said cups.

10. A can filling machine having a measuring device comprising upper and lower turrets having telescopic measuring cups, a hollow shaft connected to the lower turret for rotating the device, a shaft longitudinally slidable within said hollow shaft and having its upper end connected to said upper turret and its lower end extending from the bottom of said hollow shaft, manually operable means on the machine frame and connecting the extending end of said internal shaft for moving same longitudinally to alter the capacity of said cups, and a finger rotated by the operation of said last named means for indicating the capacities of said cups.

11. A can filling machine having a measuring device comprising upper and lower turrets having a series of cooperating telescopic flanges forming cups, said device having a driven hollow shaft connected to the lower turret and having a shaft connected to the upper turret and slidable in said hollow shaft for adjusting the capacities of the telescopic cups, and mechanism for raising and lowering said internal shaft, said mechanism comprising a stirrup engaging the lower end of said shaft, and having vertically fixed rotatable screw means for raising and lowering said stirrup.

12. A can filling machine having a measuring device comprising upper and lower turrets having a series of cooperating telescopic flanges forming cups, said device having a driven hollow shaft connected to the lower turret and having a shaft connected to the upper turret and slidable in said hollow shaft for adjusting the capacities of the telescopic cups, and mechanism for raising and lowering said internal shaft, said mechanism comprising a stirrup engaging the lower end of said shaft, and having gear operated vertically fixed rotatable screw means for raising and lowering said stirrup.

13. A can filling machine having a measuring device comprising upper and lower turrets having a series of cooperating telescopic flanges forming cups, said device having a driven hollow shaft connected to the lower turret and having a shaft connected to the upper turret and slidable in said hollow shaft for adjusting the capacities of the telescopic cups, a dial for said shaft, and means operated by sliding said internal shaft for indicating the capacities of said cups on said dial.

14. A can filling machine having a measuring device comprising upper and lower turrets having a series of cooperating telescopic flanges forming cups, said device having a driven hollow

shaft connected to the lower turret and having a shaft connected to the upper turret and slideable in said hollow shaft for adjusting the capacities of the telescopic cups, manually operable means for raising and lowering said internal shaft, and means operated by the mechanism for sliding said shaft to indicate the capacities of said cups.

15. A can filling machine having a measuring device comprising upper and lower turrets having a series of cooperating telescopic flanges forming cups, said device having a driven hollow shaft connected to the lower turret and having a shaft connected to the upper turret and slideable in said hollow shaft for adjusting the capacities of the telescopic cups, manually operable means for raising and lowering said internal shaft, and dial and finger means operated by the mechanism for sliding said shaft to indicate the capacities of said cups.

16. A can filling machine having a measuring device comprising upper and lower turrets having a series of cooperating telescopic flanges forming cups, said device having a driven hollow shaft connected to the lower turret and having a shaft connected to the upper turret and slideable in said hollow shaft for adjusting the capacities of the telescopic cups, mechanism for raising and lowering said internal shaft, said mechanism comprising a stirrup engaging the lower end of said shaft, and having vertically fixed rotatable screw means for raising and lowering said stirrup, a dial, a finger for indicating the measuring cup capacity on said dial, said finger being operated by the operation of said stirrup.

17. A can filling machine having a measuring device comprising upper and lower turrets having a series of cooperating telescopic flanges forming cups, said device having a driven hollow shaft connected to the lower turret and having a shaft connected to the upper turret and slideable in said hollow shaft for adjusting the capacities of the telescopic cups, mechanism for raising and lowering said internal shaft, said mechanism comprising a stirrup engaging the lower end of said shaft, and having vertically fixed rotatable screw means for raising and lowering said stirrup, a dial, a finger for indicating the measuring cup capacity on said dial, a pinion on said finger, and rack means operated by the stirrup for rotating said finger when the internal shaft is raised or lowered.

18. A can filling machine having a measuring device comprising upper and lower turrets having a series of cooperating telescopic flanges forming cups, said device having a driven hollow shaft connected to the lower turret and having a shaft connected to the upper turret and slideable in said hollow shaft for adjusting the capacities of the telescopic cups, mechanism for raising and lowering said internal shaft, said mechanism comprising a stirrup engaging the lower end of said shaft, and having vertically fixed rotatable screw means for raising and lowering said stirrup, and manual means for operating said screw means.

19. A can filling machine having a measuring device comprising upper and lower turrets having a series of cooperating telescopic flanges forming cups, said device having a driven hollow shaft connected to the lower turret and having a shaft connected to the upper turret and slideable in said hollow shaft for adjusting the capacities of the telescopic cups, mechanism for

raising and lowering said internal shaft, said mechanism comprising a stirrup engaging the lower end of said shaft, and having gear operated vertically fixed rotatable screw means for raising and lowering said stirrup, and manual means for operating said gears.

20. A can filling machine having a measuring device comprising upper and lower turrets having a series of cooperating telescopic flanges forming cups, said device having a driven hollow shaft connected to the lower turret and having a stub shaft connected to the upper turret and extending into the upper end of said hollow shaft and slidable therein, and a shaft below said stub shaft and engaging the same slidable in said hollow shaft and extending from the lower end of said hollow shaft for raising and lowering the upper turret to adjust the capacities of the telescopic cups.

21. A can filling machine having a measuring device comprising upper and lower turrets having a series of cooperating telescopic flanges forming cups, said device having a driven hollow shaft connected to the lower turret and having a stub shaft connected to the upper turret and extending into the upper end of said hollow shaft and slidable therein, a shaft below said stub shaft and engaging the same slidable in said hollow shaft and extending from the lower end of said hollow shaft for raising and lowering the upper turret to adjust the capacities of the telescopic cups, and manually operable means for raising and lowering said last-named shaft.

22. A can filling machine having a measuring

device comprising upper and lower turrets having a series of cooperating telescopic flanges forming cups, said device having a driven hollow shaft connected to the lower turret and having a stub shaft connected to the upper turret and extending into the upper end of said hollow shaft and slidable therein, a shaft below said stub shaft and engaging the same slidable in said hollow shaft and extending from the lower end of said hollow shaft for raising and lowering the upper turret to adjust the capacities of the telescopic cups, and gear operated screw mechanism for raising and lowering said internal shaft.

23. A can filling machine having a measuring device comprising upper and lower turrets having a series of cooperating telescopic flanges forming cups, said device having a driven hollow shaft connected to the lower turret and having a stub shaft connected to the upper turret and extending into the upper end of said hollow shaft and slidable therein, a shaft below said stub shaft and engaging the same slidable in said hollow shaft and extending from the lower end of said hollow shaft for raising and lowering the upper turret to adjust the capacities of the telescopic cups, a dial, a rotatable finger for indicating the capacities of the measuring cups, and manually operable means for raising and lowering said last-named shaft to regulate the capacities of said cups, said means when operated in turn rotating said dial finger.

CHARLES H. AYARS.
